UNITED STATES PATENT OFFICE

92,498

DESIGN FOR A RADIOCABINET

Leo R. Slaton, Detroit, Mich., and Avigdor M. Morgan, Belmont, Mass.; said Morgan assignor to Shortwave & Television Corporation, Boston, Mass., a corporation of Delaware

Application September 28, 1933, Serial No. 49,374

Term of patent 3½ years

To all whom it may concern:

Be it known that we, LEO R. SLATON, a citizen of the United States, a resident of Detroit, in the county of Wayne, State of Michigan, and AVIGDOR M. MORGAN, a citizen of the United States, a resident of Belmont, in the county of Middlesex, State of Massachusetts, have invented a new, original, and ornamental Design for Radio Cabinets, of which the following is a specification, reference being had to the accompanying drawing, forming part thereof.

Figure 1 is a perspective view of a radio cabinet, showing our new design.

Figure 2 is a top plan view of the design.

We claim:

The ornamental design for a radio cabinet, as shown.

LEO R. SLATON.
AVIGDOR M. MORGAN.
